(57) **CLAIM**

The ornamental design for a part of dashboard for vehicles, as shown and described.

DESCRIPTION

FIG. 1 is a front perspective view of the part of dashboard for vehicles showing my design;
FIG. 2 is a front elevation view thereof;
FIG. 3 is a right-side view thereof;
FIG. 4 is an enlarged front view thereof;
FIG. 5 is a left-side view thereof;
FIG. 6 is a top plan view thereof;
FIG. 7 is a bottom view thereof; and,
FIG. 8 is a rear elevation view thereof.
Portions of the dashboard shown in broken lines form no part of the claimed design.
